OR D 18,749

Design No. 18,749, dated November 20, 1888.

UNITED STATES PATENT OFFICE.

CANDACE WHEELER, OF NEW YORK, N. Y.

DESIGN FOR A CURTAIN FABRIC.

SPECIFICATION forming part of Design No. 18,749, dated November 20, 1888.

Application filed October 11, 1888. Serial No. 287,854. Term of patent 7 years.

To all whom it may concern:

Be it known that I, CANDACE WHEELER, a citizen of the United States, residing at New York, in the county of New York and State of New York, have invented a certain new and original Design for Fabrics for Curtains and Draperies; and I do hereby declare the following to be a full, clear, and exact description of the invention, such as will enable others skilled in the art to which it appertains to make and use the same.

My design is illustrated in the accompanying drawing, which represents a portion of a silk fabric for curtains, draperies, hangings, &c.

The design consists, first, in a groundwork or body of alternate light stripes *a* and dark stripes *b*. Upon this ground and multiplied indefinitely over the entire area of the fabric are conventionalized representations of cherry-blossoms, together with the leaves and the stalks or stems which support them. These

are arranged relatively to the alternating light and dark stripes of the fabric so that the dark leaves *c* appear principally as superimposed upon the light stripes and the white or light-colored blossoms *d* upon the dark stripes, forming contrasts of color throughout the whole extent of the fabric. 25

I claim—

The design for fabrics herein described and shown, the same consisting of a groundwork of alternating light and dark stripes and representations of cherry blossoms and leaves upon such groundwork, substantially as set forth. 30

In testimony whereof I have affixed my signature in presence of two witnesses.

CANDACE WHEELER.

Witnesses:

WM. TRUSLOW,
THEODORE S. MIZE.
